UNITED STATES PATENT OFFICE.

HORACE WEEKS, OF BOSTON, MASS., ASSIGNOR TO THE CORRUGATED WIRE FASTENING COMPANY, OF HARTFORD, CONN.

NAILING-MACHINE.

SPECIFICATION forming part of Letters Patent No. 280,267, dated June 26, 1883.

Application filed April 20, 1883. (No model.)

To all whom it may concern:

Be it known that I, HORACE WEEKS, of Boston, in the county of Suffolk and State of Massachusetts, a citizen of the United States, have invented a new and useful Improvement 5 in Nailing-Machines, of which the following is a full, clear, and exact description, reference being had to the accompanying drawings, forming a part of this specification, in which—

10 Figure 1 is a front elevation of the cutting-off slide with the driver in position above it. Fig. 2 is a perspective of the movable and carrying jaw of the cut-off. Fig. 3 is a perspective of the stationary jaw of the cut-off. Fig. 15 4 is a longitudinal section of the two jaws of the cut-off on a horizontal plane with the wire from which the nail or tack is to be cut in its first position. Fig. 5 is a transverse section of the two jaws on a vertical plane along the 20 line x x of Fig. 4. Fig. 6 is a horizontal longitudinal section of the two slides after a cut has been made. Fig. 7 is a vertical transverse section of the two jaws with their nail on the line y y of Fig. 6, and with the nail just ready 25 to drive.

This invention relates to an improvement in the tacking-machines manufactured by the Corrugated Wire Fastening Company, and to the tack or nail made by the said machine.

30 These machines are patented by Letters Patent No. 225,527, dated March 16, 1880, and No. 241,550, dated May 17, 1881, to Albion Knowlton, of Boston, and the modification thereof, which constitutes the present invention, is entirely in the cutting-off and carrying device, and in the form of fastener, nail, or tack made by it. The specific organization and the means 35 of driving the cut-off and carrier are described to be like those of the patent of 1881, referred to, and the principal mechanical change is in the form and relation of the cut-off and carrier, called "K" in that patent, and in one of its guides or ways. In the machine of the 40 Knowlton patent of 1881, on which this is an improvement, the top of the cut-off or carrier severs the nail or wire and carries it below the driving-bar by the same motion employed in the improvement; but there is a change of 45 shape and relation of the cutting and carrying slide, which produces cuts in three places in

stead of one, and hence a different nail, and one of much greater importance and value.

Figs. 8 and 9 are two views of the nail. The nail which I desire to produce is made from a continuous wire of almost any even cross-section—square, round, oval, or prismatic—or from such wire horizontally corrugated, and this nail has four principal parts. h is the head, which is of the full cross-section of the wire. b is the barb of the head, produced by horizontal or beveled undercutting of the wire in cutting away to make the shank. s is the shank of the nail, which is tapered pretty uniformly from head to point, being of about one-half the size of the original wire 65 close to the head, and tapering at the point to nearly or quite a chisel edge. p is the point.

It will be observed that in case this nail with an overhanging part, as shown, be driven into stock against a clinching-surface—such, 70 for instance, as the iron bottom of a last—the point is so thin and slender that it will readily curve back into the stock and clinch on one side, while the overhanging barb b of the head, produced by the beveled undercutting, will 75 form a clinching-surface beneath the head and will compress the stock upon the shank of the nail, so as to increase its binding force by friction against the particles of stock.

In order to make this nail, the improved 80 cut-off and carrying-jaws referred to (shown in Figs. 1 to 7) are employed. Of these, A is the removable jaw and B is the fixed jaw. The offsets of the movable jaw are shown at C. The movable jaw is provided with a projecting cutting-flange, as shown at D, Fig. 2, beveled to form the overhanging barb, if desired, and the stationary jaw has an oppositely-beveled surface, E, Fig. 3, against which the under surface of the projecting flange D of 90 the slide A fits and slides. Through the flange D is made a hole, f , of proper size for the passage of the wire, as in the patent of 1881, referred to, and the wire is fed down through it at appropriate distances, according to the feed-gage of the machine. As the wire feeds down it enters into a cavity or groove, g , in the movable jaw A and an opposite cavity, g' , in the fixed jaw B, and these grooves are made with cutting-edges, so that 100

the wire, when the slide A is moved across the slide B, shall be cut in a proper form longitudinally, as shown in Figs. 8 and 9, and the under-cut of the head, made by the cutting-
5 edge of the surface E of the slide B and the adjacent edge of the under surface of the flange D of the slide A passing over each other, which under-cut, if beveled upward and inward, will form the overhanging barb b of the
10 nail, Figs. 8 and 9. The edge of the hole f in the upper surface of the movable jaw A cuts off the wire against the side of the guide-
tube, (called "K" in the Knowlton patent of 1880,) through which the wire is fed, so that
15 there is inserted in the carrier-jaw A a par-
ticularly-formed nail when said jaw is moved the width of the hole f, and the waste cut-off from the nail remains in the cavity g' of the stationary jaw D, as indicated in Fig. 5. The
20 form of the nail which remains in the carrying-jaw A is substantially as indicated in Fig. 7 at h p. The movable jaw A has now be-
come a carrier, and carries forward the nail to a position under the driving-bar I, as indi-
25 cated in Fig. 1, in which w is the wire and I
is the driving-bar, and the position of the
jaws A B is as shown in Fig. 6. When the
hole f and cavity g of the movable jaw A are
30 beneath the driving-bar I they coincide with
the cavity K of the fixed jaw B, and thus the
nail is in a position where it can be driven
down into the stock by means of the driving-
bar I, (shown,) while at any other position
35 the under-cut head and barb b are supported
on the top of the fixed jaw B, and consequently
cannot be forced downward. At the same
time that the cavity g of the movable jaw A
coincides with the cavity K of the fixed jaw
40 B the cavity g' of the fixed jaw B will coincide
with the cavity l of the movable jaw A, and
there will be a clearance made for the waste
of the nail, which waste will drop out and the
machine be ready for a back-stroke, a second
45 feeding of the wire, a second cutting off, a sec-
ond driving, and so on.

It will be noticed that the fixed jaw of the sliding shears B has a slightly undercut bevel in order to taper the point of the nail, and that the cavity g', which forms the cutting-off de-
50 vice, is somewhat enlarged longitudinally at its bottom, and its cutting-edge curved, so as to give a draw-cut, a good clearance, and an easy drop for the waste; and it will also be noticed that this under-cut formation of the sta-
55 tionary jaw requires for making a tapering nail that the cavity K in the fixed jaw B, through which the nail is driven, should be in cross-section about a half-circle at the top and rather more than a half-circle at the bottom,
60 and it will be observed that this, in the de-

scent of the nail into the stock, steadies it un-
der the blow of the driving-bar I.

It will also be noticed that the front sur-
face of the movable jaw A is beveled comple-
mentarily, so as to form a close sliding blade 65
for cutting-off purposes, and that the cavity g
is about the size of a half-circle at the top and
less than a half-circle at the bottom. The cav-
ity l is made large, so that the waste of the
wire shall not be held, but may freely drop out 70
when the machine has made its stroke and
driven its nail.

It will also be observed, on reference to the
Knowlton patent of 1881, that whereas that
cuts off only on the plane of the upper surface 75
of the carrier, the carrier A, herein described,
corresponding so far with the Knowlton carrier
K of the patent of 1881, has two additional
cutting-edges at preferably a slightly-acute
angle with each other to form the lower part 80
of the nail, and that hence a new function (cut-
ting-off) is given to the carrier-guides, (F of
the Knowlton patent of 1880,) and it is to these
modifications of the machine that my inven-
tion relates. 85

It will also be observed that the nail may be
cut without a bulging or undercut head, if de-
sired; but I prefer the barb-headed nail de-
scribed.

In use of this machine wire corrugated hori- 90
zontally with substantial uniformity is the
equivalent of wire of uniform cross-section,
and almost any prismatic form may be given
to the wire.

The clearance-cavity l is a convenience rather 95
than a necessity, and may often be sufficiently
represented by an easy fit between the jaws
behind hole g'.

Having thus fully described my invention,
what I claim, and desire to secure by Letters 100
Patent of the United States, is—

1. The stationary jaw B, provided with cut-
ting-edge cavity g' and driving-recess K, in
combination with movable jaw A, provided
with cutting-edge cavity g and clearance-recess 105
l, substantially as and for the purposes de-
scribed.

2. The stationary jaw B, provided with cut-
ting-edge cavity g' and driving-recess K, in
combination with movable jaw A, provided 110
with cutting-edge cavity g and cutting-flange
D, substantially as described.

3. In the stationary jaw B, the cavity g',
vertical on its dead side, enlarged on its lower
side, and having a draw-cutting edge, substan- 115
tially as and for the purposes described.

HORACE WEEKS.
